UNITED STATES PATENT OFFICE.

WILLIAM C. DILLON, OF FORT DODGE, IOWA, ASSIGNOR TO DILLON BANK PROTECTION SERVICE, A CORPORATION.

SHEARING DEVICE AND SAFE ATTACHMENT FOR AUXILIARY VAULT-DOOR LOCKS.

Application filed April 17, 1922. Serial No. 553,593.

To all whom it may concern:

Be it known that I, WILLIAM C. DILLON, a citizen of the United States, and a resident of Fort Dodge, in the county of Webster and State of Iowa, have invented a certain new and useful Shearing Device and Safe Attachment for Auxiliary Vault-Door Locks, of which the following is a specification.

- 10 The object of my invention is to provide a shearing device attachment for auxiliary vault and safe door locks, the parts being of simple durable and comparatively inexpensive construction.
- 15 My invention relates to an attachment especially designed to shear a flexible element for releasing an auxiliary locking device when the combination lock on the vault or safe door is pushed inward.
- 20 Still another object is to provide a frangible plate extending over the combination lock and so arranged that when the combination lock is pushed inward, the plate will become broken and release the auxiliary locking device.

With these and other objects in view, my invention consists in the construction, arrangement and combination of the various parts of my device, whereby the objects contemplated are attained, as hereinafter more fully set forth, pointed out in my claims, and illustrated in the accompany drawings, in which:

Figure 1 is an elevation of a portion of a vault door with my improved shearing device shown thereon.

Figure 2 is an enlarged view of the shearing device extended over the combination mechanism.

40 Figure 3 is a sectional view taken on line 3—3 of Figure 2.

Figure 4 is a detailed sectional view taken on line 4—4 of Figure 2.

Figure 5 is an elevation of a slightly modified form of my device; and

Figure 6 is a sectional view taken on line 6—6 Figure 5.

In the accompanying drawings, I have used the reference numeral 10 to indicate generally a vault or safe door which is provided with an inwardly extending flange 11 on its inner side near its edge.

I have used the reference numeral 12 to indicate the door jamb. A bolt locking mech-

anism is arranged on the vault door 10 and the bolts 13 thereof are designed to slide through openings formed in the flange 11. A combination lock 14 is provided on the vault door and is designed to cooperate with the locking members 15 which are secured to the bolt members 13. The parts just described are of the ordinary construction now commercially used on vault doors.

Mounted on the flange 11 of the vault door 10 is an auxiliary lock device A. The auxiliary lock device A is of the type illustrated in the Horspool Letters Patent, dated January 13, 1922, Number 1,402,499; and my Letters Patent dated January 31, 1922, Number 1,404,937.

The auxiliary locking device is designed to coact with the bolt mechanism for preventing their unauthorized movement. In order to hold the auxiliary locking device normally inactive, I provide a flexible element 16.

The flexible element 16 has one of its ends secured to the locking bar of the auxiliary lock device and has its other end anchored to the door as at 17. When the flexible element 16 is broken, the auxiliary locking device will operate and move into the path of travel of the bolt mechanism for preventing its operation.

In order to provide a means for breaking or shearing the flexible connection when the combination lock 14 is punched inward, I have provided the following described mechanism.

I provide a guide stud 18 which may be screw threaded into the vault door 10. The guide stud 18 is arranged near one side of the combination lock 14. On the opposite side of the combination lock 14 and screwed into the vault door 10 is a bolt 19. A sleeve 20 is extended around the bolt 19. Connecting the guide stud 18 and the bolt 19 is a plate 21.

The plate 21 is provided with a pair of openings which receive the guide stud 18 and the bolt 19. One end of the plate 21 rests upon the sleeve 20. The guide stud 18 is provided with a small opening 22, the purpose of which will be hereinafter more fully set forth.

Extending through the opening 22 is the flexible element 16. The arrangement just mentioned causes the flexible element to be

extended across the combination lock 14. The flexible element also tends to hold the end of the plate on the guide stud 18 in position.

5 A small tube 23 of very soft material is extended into the opening 22 and has the flexible element extended therethrough.

From the construction of the parts just described it will be seen that when anyone 10 attempts to get into the vault by punching the combination lock inward he will cause the plate 21 to be pushed inward thus shearing the flexible element 16 and releasing the auxiliary locking device. The ends of the 15 tube 23 project out beyond the edges of the opening 22, so that when the plate 21 is moved a small amount, it will engage the tube 23 rather than cutting the flexible element 16. This permits the manipulation of 20 the combination lock by some one authorized to do so without the danger of shearing or weakening the flexible element 16. The soft tube 23, will offer no resistance to the great 25 amount of force, which is required to punch the combination lock inward and permits the flexible element 16 to be severed.

The flexible element is extended across the combination lock and through the guide stud 18 and will permit the operation of the 30 locking device A when the wire is burned.

Sometimes burglars attempting to gain 35 access into the vault will punch the combination lock, or burn around the combination lock so that the bolt mechanisms will be free to operate. The flexible element is so arranged that the punching in of the combination lock or the burning of a vault door will cause it to be severed.

In Figures 5 and 6 of the drawings, I 40 have shown a slightly modified form of my invention in which form, I provide a pair of bolts 24 which are screwed into the vault door 10. The bolts 24 are provided with sleeves 25. Resting upon the sleeves 25 and 45 below the heads of the bolts 24 is a frangible plate 26.

The plate 26 is preferably made of glass or some other brittle material. The plate 26 is provided with an opening 27 near its center, in which opening is mounted a stud 28.

The stud 28 is provided with an opening 29 through which may be extended the flexible element 16.

In this form of invention the flexible element 16 passes below the plate 26. The stud 28 is held in position against movement in one direction by the combination mechanism 14, and against movement in the opposite direction by the flexible element 16.

60 The punching in of the combination lock will cause the stud to be moved inward, thus breaking the frangible plate 26 and releasing the stud 28. As soon as the stud 28 is released the auxiliary locking device is then operated.

Flexible element 16 is also released when stud 28 is moved, and the opening in stud 28 permits the flexible element 16 to slide through it in event the flexible element is released due to burning gases being applied 70 to the door.

It will be seen that my device is very simple and that I have provided a very efficient device for releasing the flexible element so as to permit the auxiliary locking device 75 to operate when the combination mechanism is punched inward, or the flexible element 16 is burned.

Some changes may be made in the construction, and arrangement of the various 80 parts of my device without departing from the essential features and purposes of my invention, and it is my intention to cover by my claims, any modified forms of structure or use of mechanical equivalents, which may 85 be reasonably included within their scope.

I claim as my invention:

1. In combination with a vault or safe 90 door having locking and combination mechanisms thereon, an auxiliary locking device and a flexible element for normally holding the auxiliary locking device inoperative, a means for severing said flexible element, said last means including a plate extended over the combination lock, a stud having an opening 95 therein extended through the plate and having the flexible element guided therethrough, whereby the inward movement of the combination lock will cause the plate to shear the flexible element. 100

2. In combination with a vault or safe 105 door having locking and combination mechanisms thereon, an auxiliary locking device and a flexible element for normally holding the auxiliary locking device inoperative, a means for severing said flexible element, and said last means including a plate extended over the combination lock, a stud extended through an opening in the plate, the opening in the plate being of substantially the same 110 size as the stud, said stud having an opening 115 therein through which the flexible element is guided whereby the inward movement of the combination lock, due to the punching in of the combination lock, will cause the flexible element to be sheared. 115

3. In combination with a vault or safe 120 door having locking and combination mechanisms thereon, an auxiliary locking device and a flexible element for normally holding the auxiliary locking device inoperative, a frangible plate extended over the combination lock, a guide stud having an opening 125 therein mounted on the frangible plate, said flexible element being extended through the guide stud, the parts being so arranged that the punching in of the combination lock will break the frangible plate, thereby releasing the guide stud as specified. 130

4. In combination with a vault or safe 130

door having locking and combination mechanisms thereon, an auxiliary locking device and a flexible element for normally holding the auxiliary locking device inoperative, a
5 frangible plate extended over the combination lock, means on said frangible plate for guiding the flexible element thereover, the

parts being so arranged that the punching i
of the combination lock will break th
frangible plate and release the flexible ele
ment for permitting the auxiliary lockin
device to operate.

Des Moines, Iowa, February 7, 1922.

WILLIAM C. DILLON.
